(57) **CLAIM**

The ornamental design for a modular grid, as shown and described.

DESCRIPTION

FIG. 1 is a front perspective view of a modular grid, showing our new design.

FIG. 2 is a left side elevation view of the modular grid of FIG. 1.

FIG. 3 is a right side elevation view of the modular grid of FIG. 1.

FIG. 4 is a front elevation view of the modular grid of FIG. 1.

FIG. 5 is a rear elevation view of the modular grid of FIG. 1.

FIG. 6 is a top plan view of the modular grid of FIG. 1.

FIG. 7 is a bottom plan view of the modular grid of FIG. 1; and,

FIG. 8 is a front perspective view of the modular grid of FIG. 1, showing an upper bar used with the modular grid.

The broken lines in the drawings form no part of the claimed design.
